UNITED STATES PATENT OFFICE.

HARRY W. DYCH, OF PHILADELPHIA, PENNSYLVANIA.

GLASS-CUTTING PROCESS FOR TRANSLUCENT ARTICLES.

Application filed October 25, 1924. Serial No. 745,815.

To all whom it may concern:

Be it known that I, HARRY W. DYCH, a citizen of the United States, residing at Philadelphia, in the county of Philadelphia and State of Pennsylvania, have invented new and useful Improvements in Glass-Cutting Processes for Translucent Articles, of which the following is a specification.

My invention relates to new and useful 10 improvements in a glass cutting process for translucent articles and more particularly to the cutting of designs on electric light bulbs or lamps which are translucent because of a frosted or painted surface or which are 15 made translucent or semi-opaque in any other manner whatsoever.

In cutting designs, figures or the like on transparent electric lamps or other bulbous articles a portion of the translucent surface 20 is removed in order to provide a transparent part through which a distant wall will be readily visible, then cutting the design or figure on the distant translucent wall in the ordinary manner and then again 25 treating the transparent portion so as to again become translucent to a degree corresponding with or approximating the translucency of the balance of the article.

The fundamental steps of the process set 30 forth above may be enlarged upon by adding the steps required to first make the bulbous article translucent which may be done by painting, acid etching, steel brush grinding with carborundum or other desirable 35 method; next to polish the cutting in some well known manner as by the use of cork pumice; and then removing the mark left between where the re-surfacing joins with the original translucent surface. Then 40 again the fundamental process may be decreased by eliminating the step or removing the translucent surface from a part of the article which could be done where partly translucent bulbs are bought on the market.

45 With these ends in view, this invention consists in the details of construction and combination of elements hereinafter set forth and then specifically designated by the claims.

50 In order that those skilled in the art to which this invention appertains, may understand how to make and use the same, I will describe its construction in detail, referring by numerals to the accompanying

drawings forming a part of this application, 55 in which:—

Fig. 1, is a side elevation of an electric lamp or bulb of usual construction showing the entire glass body formed translucent.

Fig. 2, is a similar view illustrating the 60 completion of the step in the process where a portion of the glass body has been made transparent.

Fig. 3, is an end view of the electric light bulb illustrating that step in the process 65 at the completion of the cutting.

Fig. 4, is a side elevation of a finished electric light bulb produced by the use of my process.

In carrying out my invention as here embodied, I take an ordinary electric lamp bulb including a glass body 2 and a threaded metal plug 3 and I make the glass body portion translucent, ordinarily called frosting, by painting, acid etching or grinding the surface of the same and where the frosting is done by the grinding process 75 generally a steel brush with carborundum thereon is used.

Wherever the word frosting is used 80 throughout this description it is to be understood that it includes any way in which the outer surface of the glass body or bulb is made translucent.

The translucent or frosted glass body is 85 next treated in some desirable manner for removing a portion of the translucent or frosted surface in order to provide a transparent portion 4 in addition to the translucent portion 5, as shown in Figs. 2 and 3. 90 Where this translucent or frosted surface is formed by acid etching it may be removed by the use of a cork wheel fed with pumice as is well known.

When the glass body or bulb is in this 95 condition the wall of said body or bulb opposite the transparent portion is readily visible through said transparent portion and due to the semi-transparent condition of the translucent portion the cutting wheel 100 may be discerned by the operator during the cutting of designs or figures 6 thereon.

After a translucent portion of the bulb 105 has been cut it is polished so as to give a finished sheen to the cutting.

Next the transparent portion of the bulb is refrosted or again made translucent by refrosting said transparent portion in the

same manner as the entire body was originally frosted or made translucent and any mark which may be left between the original frosting and the refrosting is then removed by the use of carborundum, sand, emery or the like which is rubbed in until the two frosted portions are of substantially the same density so that for all practical purposes the meeting line will be obliterated. 5

10 From the foregoing description it will be particularly noted that electric lamps or bulbs treated by this process not only makes the article ornamental but permits the passage of more of the light rays without greatly reducing non glaring properties of a frosted bulb. 15

Of course I do not wish to be limited to the precise methods described for carrying out the several steps of the process as these 20 may be varied within the limits of the appended claims without departing from the spirit of my invention.

Having thus fully described my invention, what I claim as new and useful is:—

23 1. The process of cutting translucent bulbous articles which comprises the cutting of a design on a translucent surface by viewing the cutting operations through a transparent wall of the article and then making the transparent portion translucent.

2. The process of cutting figures on bulbous translucent articles comprises removing a portion of the translucent surface of the article so as to provide a transparent portion, then cutting the translucent portion by viewing the cutting operations through the transparent portion and then making the transparent portion translucent. 35

3. A glass cutting process which comprises making a bulbous article partly translucent thereby leaving a transparent portion, 40

cutting the translucent portion by viewing the cutting operations through the transparent portion and then making the transparent portion translucent. 45

4. A process for cutting bulbous glass articles which comprises the treating of the exterior surface of said article to make the same translucent, then removing a portion of the translucent surface to provide a transparent portion, then cutting the translucent surface by viewing the cutting operations through the transparent portion, and then again treating the transparent portion to make it translucent. 50 55

5. A process for cutting bulbous glass articles which comprises the treating of the exterior surface of said article to make the same translucent, then removing a portion of the translucent surface to provide a transparent portion, then cutting the translucent surface by viewing the cutting operations through the transparent portion, then again treating the transparent portion to make it translucent, then polishing the cutting, and 60 then obliterating the mark of connection between the two translucent portions. 65

6. The process of cutting translucent bulbous articles which comprises the cutting of a design on a translucent surface by viewing the cutting operations through a transparent wall of the article and then making the transparent portion translucent, then polishing the cutting, and then grinding the 70 surface of the article in the region of the meeting line between the two translucent portions to substantially obliterate said meeting line. 75

In testimony whereof, I have hereunto affixed my signature.

HARRY W. DYCH.
